CLAIM

The ornamental design for a image capture device holder, as shown and described.

DESCRIPTION

FIG. 1 is a front perspective view of an image capture device holder according to the new design;

FIG. 2 is a rear perspective view of the holder of FIG. 1;

FIG. 3 is a front view of the holder of FIG. 1;

FIG. 4 is a rear view of the holder of FIG. 1;

FIG. 5 is a side view of the holder of FIG. 1;

FIG. 6 is an opposite side view of the holder of FIG. 1;

FIG. 7 is a top plan view of the holder of FIG. 1; and,

FIG. 8 is a bottom plan view of the holder of FIG. 1.

The broken lines of the claimed design and the spaces therein are included for illustrating environmental aspects only and form no part of the claimed design.

1 Claim, 7 Drawing Sheets
